COMBINED TOY MIXER AND SCALE

Gordon A. Barlow, Chicago, and Norman T. McFarland,
Mayview, Ill., assignors to Marvin Glass & Associates,
Chicago, Ill., a partnership

Filed Dec. 11, 1963, Ser. No. 77,753

Term of patent 14 years

(Cl. D34—15)

Fig. 1.

Fig. 2.

Fig. 3.

Fig. 5.

We claim:

The ornamental design for a combined toy mixer and scale, substantially as shown.
